(57) **CLAIM**

We claim the ornamental design for a touchless gesture customer assistance device, as shown and described.

DESCRIPTION

FIG. 1 is a front view of the touchless gesture customer assistance device of the present invention;

FIG. 2 is a left side perspective view of the touchless gesture customer assistance device shown in FIG. 1;

FIG. 3 is a right side perspective view of the touchless gesture customer assistance device shown in FIG. 1; and, FIG. 4 is a side view of the touchless gesture customer assistance device shown in FIG. 1.
